Primary Examiner — Jonathan J Han*Assistant Examiner* — Christen Pilar Brown(57) **CLAIM**

The ornamental design for a shoe, as shown and described.

DESCRIPTION

FIG. 1 is a top perspective view of a shoe, showing my new design;

FIG. 2 is a bottom perspective view thereof;

FIG. 3 is a top view thereof;

FIG. 4 is a bottom view thereof;

FIG. 7 is a front view thereof;

FIG. 8 is a rear view thereof;

FIG. 9 is an enlarged detail view of an area labeled “9” in FIG. 2;

FIG. 10 is an enlarged detail view of an area labeled “10” in FIG. 5; and,

FIG. 11 is an enlarged detail view of an area labeled “11” in FIG. 7.

The broken lines in the drawings illustrate the portions of the shoe, which form no part of the claimed design.

The dash-dot-dash broken lines encircling the enlarged views are for annotative purposes only and form no part of the claim thereof.

1 Claim, 11 Drawing Sheets(56)
